UNITED STATES PATENT OFFICE.

WILLIAM C. LIMBACH, OF MASSILLON, OHIO.

PROP.

Application filed February 21, 1924. Serial No. 694,333.

To all whom it may concern.

Be it known that I, WILLIAM C. LIMBACH, a citizen of the United States, residing at Massillon, in the county of Stark and State 5 of Ohio, have invented new and useful Improvements in Props, of which the following is a specification.

This invention relates to props, such as clothes line props and the like, and contemplates an adjustable structure whereby 10 the length of the prop can be varied to meet all requirements.

More specifically stated, the invention provides a prop made up of a plurality of 15 relatively movable slidably associated sections susceptible of independent movement so that the length of the prop can be regulated as the occasion may require, and provided with means for holding the sections 20 fixed relatively in their adjusted positions.

The nature and advantages of the invention will be better understood when the following detailed description is read in connection with the accompanying drawings, 25 the invention residing in the construction, combination and arrangement of parts as claimed.

In the drawings forming part of this application, like numerals of reference indicate 30 similar parts in the several views, and wherein:

Figure 1 is a view in elevation of the prop showing the sections extended.

Figure 2 is a view taken at a right angle 35 to Figure 1.

Figure 3 is a transverse sectional view taken on the line 3—3 of Figure 1.

Figure 4 is a detail view of one of the 40 adjustable sections.

Figure 5 is a detail view of the intermediate section.

Figure 6 is a sectional view taken on the line 6—6 of Figure 1.

Figure 7 is an enlarged fragmentary view 45 showing the spring pressed catch and its relation with the prop sections.

Figure 8 is a fragmentary view showing a modified construction.

Figure 9 is a fragmentary view of an 50 other modified construction.

Referring to the drawings in detail, 10 represents what I term the end sections of the prop, these sections being arranged to slide on the opposed sides of the intermediate section 11. Of course, the prop can be made up of any number of such sections,

although three of such sections of proper dimensions form a prop whose length can be conveniently regulated for most any purpose. The prop is primarily intended for 60 use as a clothes line prop, and the upper end section 10 is thus provided with a fork 12, the limbs being closely associated by having their free ends flared to accommodate the clothes line. The limbs are held closely 65 associated by means of coil springs 18 which are supported on a transverse pin passed through said limbs, each end of the pin being formed with a head 19. The pin itself is indicated at 20, and upon inspection of Figure 1 it will be noted that the corresponding outer ends of said springs bear against said heads while the inner extremities of said springs bear against said limbs. The opposed longitudinal edges of 70 the intermediate section 11 are grooved to receive the extremities of the substantially U-shaped members 14 to hold the sections operatively associated. Manifestly, there is 75 one of these U-shaped members 14 carried by each of the end sections 10, the members 14 being arranged on the confronting sides of said sections close to the adjacent ends thereof, so that the sections can be slid along the intermediate section 11 for the 80 major portion of its length. Carried by the opposed sides of the intermediate section 15 designed to conform to the cross sectional configuration of the end sections which said 85 guides embrace. The lowermost section 10 is also provided with a substantially U-shaped clamp 16, the ends of which are turned inwardly into the grooves in the opposed longitudinal edges of the intermediate 90 section, but this member 16 supports a set 95 screw 17, which when tightened serves to clamp the lower end section and the intermediate section together and thus hold these parts fixed relatively in any given position. 100 The screw draws the clamp outwardly into effective engagement with the corresponding walls of the said grooves for this purpose, and to allow for this movement of the clamp 16, the parallel portions thereof are provided with slots 18 which receive headed pins 19 projecting from the opposite sides of the lowermost section 10. 105 For the purpose of supporting the upper section 10 in its extended position, I make 110 use of a spring pressed pivoted catch 20, this catch being pivoted as at 21 upon one lon-

gitudinal edge of the uppermost section 10. The catch consists of a plate having a straight edge 22 and an inclined edge 23 and also secured to one end of a coiled 5 spring 24, the opposite end of which is secured to a fixed point on the section 10. This spring functions to normally hold the catch disposed at a right angle to the said section 10, in which position the catch operates 10 with a stop pin 26 to support the section extended. The stop pin is arranged transversely of the intermediate section 11 projecting from the opposed longitudinal edges thereof, and also associated with a 15 spring 27 which holds one end of the pin projecting an appreciable distance beyond one edge of the intermediate section. In order to extend this upper section 10, it is only necessary to slide the section upwardly 20 on the intermediate section 11, the inclined edge 23 of the catch contacting the stop pin, which moves the catch upon its pivot against the tension of the spring 24, to allow the section 10 to be extended. In 25 other words, the catch is pivoted so that it will be automatically moved out of the way as the upper section 10 is being moved to an extended position, and when the catch passes the pin, the spring 24 returns the 30 catch to its normal position at a right angle to the section 10 in which position, the lower straight edge 22 of the catch reposes upon the pin to support the section 10 so extended. The catch is pivoted upon a metallic strip 29, one end of which is offset as at 35 30, to provide a stop for the catch, and thus limit the movement of the catch in one direction under the influence of the spring 24. When it is desired to lower the upper 40 section 10, it is only necessary to press upon one end of the pin 26 moving it to an out of the way position and allow the section 10 together with the catch to slide downwardly upon the intermediate section 11. Obviously, 45 the length of the prop can be varied by simply adjusting the lower section with relation to the intermediate section 11 after which the set screw is tightened to hold these parts fixed relatively, or the upper section 10 can be adjusted with relation to the intermediate section, independently of any adjustment of the lower section 10. It is to be also noted that when the prop is not in use, the end sections can be moved 50 toward each other to materially reduce the size of the prop, so that it can be stored or packed away in a comparatively small space.

In Figure 8, I have shown a modified construction wherein the upper section 10' 60 of the prop is slotted at one end to receive the body of the line receiving fork 12'. This fork is formed from a single piece of material bent upon itself to provide relatively movable limbs, and a portion of these 65 limbs are arranged in contacting engagement and positioned within the slot formed in the upper end of this section 10'. The fork is held associated with the prop section by means of the staples 13' which are driven 70 into the prop section 10 straddling the edge of the fork as shown in Figure 8, while the bolt or other suitable fastening element 14' is passed through the contacting portions of the limbs of said fork and also through the 75 prop section 10.

In Figure 9, I have shown another modified form of the invention, wherein the U-shaped clamp 16' is held associated with the section 10' of the prop by means of a 80 staple 15' in contra-distinction to the slot and pin arrangement illustrated in Figure 1. This clamp carries the usual set screw 17' which when tightened serves to clamp the lower section 10' to the intermediate 85 section 11'.

While it is believed that from the foregoing description, the nature and advantages of the invention will be readily apparent, I desire to have it understood that I do not 90 limit myself to what is herein shown and described, and that such changes may be resorted to when desired as fall within the scope of what is claimed.

Having thus described the invention, I 95 claim:

A prop of the character described comprising upper and lower end sections, and an intermediate section, the opposed longitudinal edges of the intermediate section 100 being grooved, substantially U-shaped members carried by the adjacent ends of the end sections and designed to be received by said grooves, guides supported by the intermediate section adjacent the ends thereof 105 and slidably receiving said end sections, said end sections being substantially of independent adjustment, means for holding the lower end section fixed relatively to the intermediate section, and cooperating means 110 carried by the intermediate section and the upper end section for holding the latter in an extended position.

In testimony whereof I affix my signature.

WILLIAM C. LIMBACH.
